ARTIFICIAL RESPIRATOR

Francis T. Wallin, Brookline, Mass.

Application April 30, 1947, Serial No. 744,995

9 Claims. (Cl. 128—28)

1

This invention relates to artificial respirators, commonly known as "iron lungs," which are used to induce artificial respiration in paralysis victims, and victims of electrical shock, drowning and asphyxiation and the like, who are unable to breathe naturally. In such respirators the patient is placed bodily, except for his head, within a horizontal cylindrical chamber, which is then made air-tight, and variations of air pressure provided within the chamber, ranging usually from normal atmospheric pressure to about 40 centimeters of water vacuum, then cause the patient's lungs alternately to expand and contract, thus inhaling and exhaling air in the manner of natural breathing. In such respirators the cylindrical chamber holding the patient is formed of sheet metal, and is rigid, and the patient is placed in the chamber through the head end, which opens, by being pulled out longitudinally of the chamber, pulling the bed with it. The patient is placed on the bed, the patient's head inserted through the neck opening, the bed rolled in again, and the end is closed. Such respirators have worked well for their intended purpose in the past, but they are heavy, bulky, expensive to manufacture, difficult to transport, and the operation of inserting the patient therein is relatively difficult and slow, taking up much valuable time in critical cases.

I have accordingly devised an artificial respirator of revolutionary design, which has all the advantages of the rigid type of respirator, but which has many additional advantages. These advantages are that it is much lighter in weight, less bulky, and is collapsible to occupy half the space of the rigid type of respirator, is much less expensive to manufacture and hence can be sold at a much lower price, can be readily transported to the scene of the accident, for instance, on a light truck. In addition, the patient can be readily inserted in the respirator in an easier, simpler, and quicker manner. Furthermore, any of the parts which may deteriorate or wear, can be readily replaced at small cost.

Briefly, my invention comprises a respirator of the horizontal cylinder type, which encloses the entire body of the patient except for the head, but the cylindrical chamber, instead of being made of sheet metal and hence of rigid construction, is made of flexible or resilient material such as sheet or corrugated rubber, plastic, rubber-coated fabric or the like, and is preferably supported on circular ribs. Hence the cylindrical chamber can be expanded and contracted, in a horizontal or longitudinal direction, relative

to the fixed head end. Thus by pushing in the flexible cylindrical chamber longitudinally toward the front end, which slides back and contracts preferably in pleated folds, the chamber is opened up, and this allows ample room for the insertion of the patient upon the bed, and quick closing of the chamber by pulling back or expanding the flexible chamber to normal size and clamping it tightly to the rigid head end.

- 10 At the same time if desired, the longitudinal frame of the bed and respirator can also be made collapsible or foldable, whereby the respirator may be readily stored or transported in collapsed condition while occupying a relatively small space. By such construction, a respirator of the horizontal cylindrical chamber type having a steel frame can be reduced in weight from approximately 800 lbs. to 275 lbs., can be reduced in length, when collapsed for storage or transportation, from about 72 inches to 37 inches, and in height from about 58 inches to 38 inches, and can be sold for about one-half the present cost of the rigid cylinder type. The lower cost of manufacture permits a wholly satisfactory respirator, or more of them, to be supplied to persons, institutions, and public agencies who could not previously afford them, and in many other places, such as beaches, lakes, and resort places, which could not previously be readily equipped. My collapsible chamber respirator thus is even lower in cost than the jacket type of respirator, which fits over the patient like a jacket and is sealed, and consequently constricts the patient, at the waist and arms, as well as at the neck, and yet has none of the disadvantages of the jacket type of equipment.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Additional advantages of my device will appear in the following specification and accompanying drawings, in which

Fig. 1 is a side elevation of my respirator in closed position;

Fig. 2 is a side elevation of the same device in open position;

2

3

Fig. 3 is a plan view of a section of the side frame;

Fig. 4 is a vertical section on an enlarged scale on lines 4—4 of Figs. 1 and 3;

Fig. 5 is a side elevation of my respirator in collapsed form;

Fig. 6 is a side elevation of the collapsible tube with a part in section;

Fig. 7 is a plan view of the frame with the collapsible tube removed; and

Fig. 8 is a side elevation of a rigid non-collapsible form of my respirator in its open position.

In the drawings 10 represents the frame of my machine generally, and includes the legs 11 mounted on casters 12, and the side rails 13. To be considered as an integral part of the frame, because rigidly fixed thereto, is the vertical head-end section 15, and the foot-end frame section 18. The head-end section 15, preferably a metal spinning constitutes the head-end wall of the casing 25 to be described, and it is to be understood that the head of the patient passes through an opening provided in said end section 15 and mounted thereon is any suitable resilient collar generally indicated at 16 which includes a rubber closure adjustably adapted to fit snugly around the neck of the patient and to form an air tight seal therewith. It will be understood that a head-rest (not shown) is provided to support the head of the patient. The foot-end frame section 18 is merely an annular ring rigidly mounted on frame 10, and may be regarded as the foot-end wall of the casing 25, to be described. The foot end would normally be closed by a sheet metal wall section similar to the front or head end section 15, but in the device here shown the bellows-like mechanism for varying the air pressure within the casing, to be described below, is also mounted on the foot-end section 18, and forms the end wall thereof.

A bed 20 is mounted on the frame 10 and includes side rails 21 and mattress 22. In the preferred form of my construction, as shown in Figs. 2 and 7 the side rails 21 are tubular elements 21a, b and c graduated in size and in which the smaller sections telescope into the larger elements to permit the respirator to be folded or collapsed into a smaller space, for storage or transportation. At the same time, for the same purpose, the side rails 13 are broken into smaller elements 13a, b and c in which elements 13b and c are pivoted at their ends and will fold or jack knife to permit the respirator to be folded into a small compact unit shown in Fig. 5. A locking dog 14 with ears 14a extending over corresponding slots cut in the side rails 13b and c prevent the sections 13b and c from falling below the horizontal position as shown in Figs. 1 and 2. In Fig. 8, a rigid non-folding, or non-collapsible type of respirator is shown.

A hollow chamber or casing 25 is mounted and supported on the frame 10, enclosing the bed 20, and is adapted also to contain the body of the patient, except for his head, of course, which, as previously stated, extends through the head-end wall 15 of the compartment. The novel feature of the present casing 25 is that it has an extensible covering of flexible material such as rubber, rubber-coated fabric, plastic, leather, or the like, instead of the rigid, sheet metal casing commonly employed. The covering 25 is preferably corrugated with alternate ridges 25a and grooves 25b, which permit the covering 25 to be expanded and contracted. Casing 25 is securely connected at its foot end to a flange 18a on the foot-end sec-

4

tion 18. The front end of the casing 25 is similarly connected to an annular frame member 28 forming part of a movable carriage 30. It is to be understood that a rubber gasket (not shown) is provided to make an air tight seal between the annular frame member 28 and the front end section 15 and that the two are clamped together by quick acting clamps, shown generally at 31. A series of annular steel ribs 32 are preferably provided for the casing 25, fitting into the ridges 25a, as shown in Fig. 6, for supporting the casing 25. The moving carriage 30 carries on its lower bottom edge a series of wheels 33 which roll in a track 34 mounted on the side of side rails 13, as shown in Figs. 1, 3 and 4. The purpose of the moving carriage 30 of course, is to permit the covering 25 to be pushed back and compressed or contracted, when frame member 28 is disconnected or unclamped from head end section 15, thus permitting the patient to be inserted in the chamber 25 on the bed 20, given nursing care, or otherwise attended to. The covering 25 is shown in its compressed or contracted form in Fig. 2.

Also mounted on the foot end section 18 at its opposite side is a bellows 35 also of corrugated flexible material, such as rubber, and designed to expand and contract longitudinally, similarly to the casing 25. The purpose of bellows 35, of course, is to produce alternate variations of pressure within the casing 25 when sealed tight. The inner end of bellows 35 is securely fixed to an opposite flange on foot end section 18, and is closed at its outer end preferably by a rigid closure 37 to which is secured the pivoted bell-crank lever 40 pivoted at 41 to a bracket 42 on end wall 37 and at 43 to an extension 38 of frame 10. Supported on an under carriage 44 is an electric motor 45 in turn connected to a speed reduction unit 46 in turn connected by arm 48 to bell crank lever 40. It will be understood that the operation of the electric motor 45 causes the bellows 35 to be pushed in and out alternately and periodically, at a speed corresponding to the natural rate of breathing of a patient. Mechanism is provided such as a Reeves pulley 46 which opens and closes to vary the speed of the compression arm 48 from 14 to 30 cycles per minute. It will be understood that as the bellows is pushed in and pulled out it creates variations in pressure within the casing 25 when sealed with the patient therein, the variations in pressure ranging from normal atmospheric pressure to 40 centimeters of water vacuum, or less as required. But the mechanism is also arranged to provide positive pressure above normal atmospheric pressure, if needed, as may be required in some electric shock cases where the muscles have lost their normal resiliency. Negative pressure or partial vacuum in the casing 25 of course, permits air to enter the patient's lungs and thereby inhale and the normal resiliency of the muscles will cause them to contract at atmospheric pressure after being expanded, and, of course, positive pressure in the casing 25 will cause the air to exit the patient's lungs and thereby exhale. A flap valve 49 mounted on end section 18 permits the air within casing 25 to exhaust ordinarily, but closing valve 49 by tightening knob 49a creates positive pressure. A pressure responsive device 50 registers the variations of pressure within the casing 25 and records it in centimeters of negative and positive water pressure. Handles 52 are provided on end casing 37 of the bellows 35 for hand operation of the bellows in case of power failure. In that

situation, of course, the arm 40 will be disconnected from the bracket 42. In the present construction the bellows 35 is shown mounted on the foot end of section 18 for the reason that this permits lowering of the height of the respirator and also simplifies transmission of power for operating the bellows. But it is to be understood that the bellows 35 may be vertically mounted beneath the casing 25 and supported on under carriage 44, as is commonly done in rigid type respirators, such as shown in Roy Patent No. 2,308,630, granted January 19, 1943, without departing from the spirit of my invention.

On the folding type of respirator shown in Figs. 1, 2 and 5, the head or collapsible end of the respirator is mounted on the carriage 55, and to prevent the head end of the respirator from tilting backward when the respirator is being folded up as in the position shown in Fig. 5, mechanism is provided, such as lever 56, which is suspended between the under carriage 44 and the front end of under carriage 55. It will be understood, however, that telescoping tubes similar to side rails 21 of the bed may also be provided for this purpose in lieu of lever 56.

The operation of my respirator will be apparent from the foregoing description. To place the patient in the respirator the covering 25 is disconnected and pushed back to the position shown in Fig. 2. The patient is then placed on the bed 20 with mattress 22 thereon, with his feet extending into the contracted covering 25, as in Fig. 2. His head is then passed through the opening provided in head-end section 15, and collar 16 is adjusted about his neck to fit snugly, thereby making the compartment air tight. The power is immediately turned on and the bellows 35 begins to operate, periodically and rhythmically contracting and expanding to cause the patient to inhale and exhale air. It will thus be seen that my respirator has many advantages over that of the rigid type, and its lightness, simplicity of operation, smaller size, and lower cost will permit such respirators to be used in many places where the larger rigid type of respirator cannot now be placed.

It is to be understood that the head-end section 15 which normally carries a head-rest extending out about 15 inches, not shown in the drawings, may be hinged on a horizontal axis at or about its point of support by the head-end legs 11, so that it may drop down out of the way, to shorten the length of the respirator during storage or transportation, and also to facilitate placing of the patient on the bed 20. It is obvious, of course, that even when so hinged, the head-end section 20 is still rigid, stationary or fixed, with respect to the movable head-end of the chamber or casing 25.

I claim:

1. In an artificial respirator, a supporting frame, a bed mounted upon said frame to support a patient thereon, a casing enclosing said bed and adapted to contain the body of a patient except for his head, a rigid wall section mounted on said frame having an opening through which the head of the patient extends, and a resilient collar in said opening forming a seal around the neck of the patient, said casing having an extensible covering of flexible material adapted to be detachably connected at its head-end to said rigid wall section, but which is movable therefrom when disconnected to open said casing, and means for varying the pressure within said casing.

2. In an artificial respirator, a supporting

frame, a bed fixedly mounted upon said frame to support a patient thereon, a hollow air-tight compartment mounted on said frame, including a casing adapted to enclose said bed and the body of a patient thereon except for his head, and a rigid wall section mounted on said frame having an opening through which the head of the patient extends and a resilient collar forming an air-tight seal about the neck of the patient, said casing having an extensible covering of flexible material adapted to be detachably connected at its head-end to said rigid wall section, but movable therefrom longitudinally, when disconnected, to open said casing, and means for varying the air pressure within said casing.

3. In an artificial respirator, a supporting frame, a bed mounted on said frame to support a patient thereon, a hollow chamber supported on said frame and enclosing said bed and adapted to contain the body of the patient except for his head, a fixed head-end section mounted on said frame having an opening therein through which the head of the patient extends and a resilient collar in said opening forming an air-tight seal around the neck of the patient, and a corrugated covering of flexible material for said chamber capable of being disconnected from said head-end section and contracted longitudinally to open said chamber, and means for alternately varying the air pressure within said chamber.

4. In an artificial respirator, a supporting frame, a bed mounted on said frame to support a patient thereon, a hollow air-tight chamber supported on said frame and enclosing said bed and adapted to contain the body of the patient except for his head, a fixed wall section mounted on said frame having an opening therein through which the head of the patient extends and a resilient collar in said opening forming an air-tight seal around the neck of the patient, and an extensible covering of flexible material mounted at its head end on a movable frame member detachably connected to said fixed wall section, and at its foot-end to a fixed frame member mounted on said supporting frame, said movable frame member being movable longitudinally, when disconnected from said fixed wall section, to compress the flexible covering to open said chamber, and means for alternately varying the air pressure within said chamber.

5. In an artificial respirator, a supporting frame, a bed mounted on said frame to support a patient thereon, a hollow air-tight chamber supported on said frame and enclosing said bed and adapted to contain the body of the patient except for his head, a fixed wall section mounted on said frame having an opening therein through which the head of the patient extends and a resilient collar in said opening forming an air-tight seal around the neck of the patient, and a corrugated covering of flexible material mounted at its head end on a movable frame member detachably connected to said fixed wall section, and at its foot-end to a fixed frame member mounted on said supporting frame, a series of ribs between said frame members supporting said covering, said movable frame member being movable longitudinally when disconnected from said fixed wall section, to compress the flexible covering to open said chamber, and means for alternately varying the air pressure within said chamber.

6. In an artificial respirator, a supporting frame, a bed mounted on said frame to support a patient thereon, a hollow air-tight casing sup-

ported on said frame and enclosing said bed and adapted to contain the body of a patient except for his head, said casing including a rigid wall section having an opening therein through which the head of the patient extends and a resilient collar in said opening forming an air-tight seal around the neck of the patient, and an extensible covering of corrugated flexible material supported at its head-end on a movable frame member detachably connected to said fixed wall section, and at its foot-end to a fixed frame member mounted on said supporting frame, and upon a series of ribs between said frame members, clamping means for detachably connecting said movable frame member to said head-end rigid wall section to permit said covering to be compressed longitudinally to open said casing, and means for varying the air pressure within said casing.

7. In an artificial respirator, a supporting frame, a bed mounted on said frame to support a patient thereon, a hollow casing supported on said frame and enclosing said bed and adapted to contain the body of a patient except for the head, said casing including a fixed wall section mounted on said frame having an opening therein through which the head of the patient extends and a resilient collar in said opening forming an air-tight seal around the neck of the patient, and an extensible covering of flexible material mounted at its head-end on a movable frame member detachably connected to said fixed wall section and at its foot-end to a fixed frame member mounted on said supporting frame, said movable frame member being movable longitudinally when disconnected to compress the flexible covering to open said casing, a bellows mounted on the foot end of said casing for alternately varying the air pressure within said casing, and power means for operating said bellows.

8. In an artificial respirator, a supporting frame, a bed mounted on said frame to support a patient thereon, said frame and bed having side-rails compressible longitudinally when said respirator is not in use, a hollow air-tight casing supported on said frame and enclosing said bed and adapted to contain the body of a patient except for his head, said casing including a

5 rigid head-end wall section having an opening therein through which the head of the patient extends and a resilient collar in said opening forming an air-tight seal around the neck of the patient, and an extensible covering of flexible material supported on a pair of frame members, the head-end member being movable and detachably connected to said rigid wall section and the foot-end member being fixedly mounted 10 on said frame, said covering being adapted to be compressed longitudinally when disconnected to open said casing, and means for alternately varying the air pressure within said casing.

9. In an artificial respirator, a supporting frame having side rails, a bed mounted on said frame to support a patient thereon, a hollow air-tight chamber supported on said frame and enclosing said bed and adapted to contain the body of the patient except for his head, a fixed 15 wall section mounted on said frame having an opening therein through which the head of the patient extends and a resilient collar in said opening forming an air-tight seal around the neck of the patient, and an extensible covering of flexible material mounted at its head end on a movable frame member detachably connected to said fixed wall section, and at its foot-end to a fixed frame member mounted on said supporting frame, said movable frame member being 20 movable longitudinally upon tracks mounted on the side-rails of said supporting frame, when disconnected from said fixed wall section, to compress the flexible covering to open said chamber, and means for alternately varying the air 25 pressure within said chamber.
